UNITED STATES PATENT OFFICE.

ELWOOD GRISSINGER, OF BUFFALO, NEW YORK.

SOUND PROJECTOR.

Application filed December 11, 1923, Serial No. 679,911. Renewed November 5, 1927.

My present invention is closely related to that claimed in my copending application Serial No. 484,240, filed July 12, 1921, and issued as Patent No. 1,477,556, certain features shown in this application being disclosed in said patent. This invention is embodied in a special form of sound projector peculiarly adapted to serve the purpose of an amplifier for phonographs, but certain features of the projector will be found useful in connection with telephone receivers and other vibratory sound producers and also in connection with other sources of sound particularly where, as in the case of human speech and music, the sounds comprise a wide range of frequencies, and particularly where it is desired to faithfully reproduce a multiplicity of sets of waves or complex waves of many frequencies, simultaneously.

A specific object of my invention is to provide an air column associated at one end with the diaphragm of the phonograph reproducer and at the other end communicating with the open air, in which the air column will be a suitable medium for development, expansion of wave front, and projecting into the open air, sound waves having a wide range of physical lengths, including sound waves of which the quarter wave length is long and requires great length of air column, and also short waves of the higher frequencies, the quarter lengths of which may be two inches or less.

In my device the waves from the tone arm or other source, discharge directly into primary expansion conduit in which the wave front is immediately afforded rapid but guided expansion in one dimension, with little or no expansion in the other dimension. This primary expansion conduit discharges through a slot-like outlet into a projector portion in which there is rapid but guided expansion in the other dimension. The primary expansion conduit may have its non-divergent walls somewhat converging towards its outlet, and the projector portion should have its non-divergent walls converging toward its outlet.

I am able to start the primary expansion in one dimension directly at the outlet of the tone arm, and this conduit may be

curved to almost any desired extent in the direction of its thinness, without danger of serious phase displacement for the short length waves. The sound beam from the outlet of the primary expansion conduit is turned abruptly through the desired angle and into the terminal or projector portion, the arrangement being so ordered that the main beam preferably crosses the plane of the vertical mouth of the projector at a sharp angle. This abrupt turning is in the direction of the thinness of the sound beam and is preferably by high angle reflection. However, the widening conduit may be curved in the direction of its thinness through an arc of 90 degrees or more if desired.

In the preferred form, the wide thin sound beam projected from the slot-like outlet of the widening conduit is caused to impinge successively upon two high angle reflectors and is then permitted guided but wide angle expansion in a vertical direction. Care should be taken to keep the dimensions of the throat through which the main beam is finally projected, as narrow as may be without choking the exit of said main beam. In practice I have found that this dimension, the distance from the bottom reflector to the roof at the nearest point, may be not very much greater, and preferably less than the inlet slot from which the primary beam is projected, although this seems to be partly an energy problem and the desideratum seems to be to have the beam "fill" the throat without choking it.

It will thus be seen that the only part of my air column in which the cross-section is big enough to afford opportunity for de-phasing reflections and diffusions is the wide angle terminal portion and here only very acute angle reflections can occur and practical use proves that such as occur are advantageous rather than otherwise.

The above principles are capable of embodiment in many specifically different forms, but I have selected for illustration herein a form in which all of the walls are very thick and are of dense stiff wood, preferably spruce. A spring metal widening conduit is sometimes desirable in connection with present day records, particularly those

of brass band music, as tending to restore some of the metallic quality to the sound which is lost through the imperfection of present day recording and reproducing methods. However, for faithful reproduction of the record the heavy non-vibratory walls are preferable.

The above and other features of my invention may be more fully understood from the following description in connection with the accompanying drawings, in which:—

Figure 1 is a vertical section along the central axis of the sound amplifier and projector on the line 1—1, Fig. 2, showing diagrammatically the path of the main "beam" and also a part of the forward diffusion thereof near the mouth of the projector.

Fig. 2 is a section on the line 2—2, Fig. 1, indicating diagrammatically the angles of divergence incidence, reflection and crossing of the flanks of the sound waves, the paths of the primary expansion and right angle reflections being projected on a plane, for this purpose.

These drawings are intended to indicate approximate sizes as well as the proportions of the parts in one desirable embodiment of my invention. The scale for Figs. 1 and 2 is indicated above Fig. 1.

In these drawings the invention is shown as adapted for a cabinet type of phonograph.

The top of the cabinet which carries the tone arm and other operating parts of the phonograph also carries the primary expansion conduit 10 and the reflectors 24, 25 and the secondary-expansion or projector portion 26, 27, 28, which opens through the side of the cabinet.

The tone arm or other source of sound discharges at 16 directly into the upper end of the air column which extends continuously through the primary and secondary expansion conduits to the outer air.

The conduit walls are all of very thick spruce, including the walls 10^a, 10^b, 10^c and 10^d of the widening conduit. The angular divergence of walls 10^c and 10^d is approximately indicated on Fig. 2. These walls are all at least one inch thick except the wall 10^b, the lower end of which is preferably thin in order to bring the widening conduit in proper relation to the reflector 24, without blocking the reflected beam from 25.

Vibration of this thinner portion, however, is prevented by providing piers 10^e, preferably of wood. These are firmly glued between 10^a and 10^b, the surfaces being drawn into most intimate engagement while the glue is wet by means of tension screws 10^f. These screws, preferably pass freely through holes 10^g in piers 10^e without engaging the sides of said holes. This leaves the end surfaces of the piers freer to take and maintain the desired position under the clamping

stress of the screw; also unequal lateral expansion or contraction of the wood cannot take effect directly on the screw.

The terminal portion of the conduit, including reflectors 24 and 25 and the side walls 28 are also one inch spruce. The length of the lower plate 26 is such that it is particularly liable to vibrate under the acoustic stresses set up by proper functioning of the projector as a whole. Hence I prefer to make the thickness of this plate greater, say 1 1/4 inch. The same tendency to vibrate is found in the roof plates 27 and 10^b, but these are so massively backed in the present construction that vibration is minimized, if not eliminated.

The trapezium shape of these plates prevents their being selectively resonant to one frequency, even for such slight vibration as they may be capable of.

By reference to the scale on the drawings, it will be seen that the inlet from the tone arm or other source is about 2 inches in diameter. Then for the next 11 inches or so through the primary expansion chamber, the air column has a front-to-rear contraction to say 1 1/4 inches, while the lateral widening in the same distance is 13 inches to 14 inches. The next 3 inches measured along the axis of the main beam, follows the reflection path, and is contained in a portion of the projector which actually measures only about 1 1/2 inches from front to rear. The path of the beam from the second reflection out to the mouth of the projector is about 7 inches to 10 inches though the shortest distance to the mouth is say 6 inches. The final expansion in the vertical direction is also limited as to angle, being preferably between top and bottom walls diverging at angles less than 90°, preferably about 60° to 70°. The horizontal width of the mouth across the face of the cabinet is preferably the same or slightly less than that of the slot outlet of the primary expansion conduit.

The waves emerging from the conduit are diverging on a spherical wave front and the angle is considerable. It results that when the end walls of the terminal portion of the conduit are parallel, as in my said application Serial No. 484,240, a substantial part of each flank of the main beam will impinge upon said walls and will be thence reflected out of the mouth of the projector. In most cases the thus deflected flanks of the beam will tend to converge toward crossing points far beyond the mouth of the projector and practically the angles are insufficient for effective lateral diffusion of the sound on each side of the direct beam. I have found, however, that improved acoustic effects, accompanied by adequate lateral diffusion may be obtained by converging the end walls as shown in Fig. 2 of this case. There seems to be a further advantage due to confining

the waves laterally (a sort of reversal of flank diffusion), probably because the vertical expansion permitted in this part of the conduit is extremely rapid and if the side walls are outwardly diverging, or even parallel, sounds of less than average volume appear not to "fill" the mouth of the projector.

The convergence of the side walls of the projector need not be more than, say, 20 degrees, that is, 10 degrees inward toward the axis, for each wall. The increase in angles of incidence of each flank of the beam, will be multiplied by two for the angles of reflection of each flank, and by four for the angles of intersection of the reflected flanks. In the proportions indicated in Fig. 2 about half of the wave front will be deflected by the sides. The extreme flanks will cross each other at obtuse angles well inside the projector and all the crossing points will be at acute angles to the plane of the mouth of the projector. It may be that the situation is analogous of the human mouth in singing, where the trained artist seems to focus the sound practically in front of the lips rather than far back in the mouth or throat. However that may be, with the construction shown, sounds of average intensity appear to originate at or near the mouth of the projector rather than further back in the conduit.

The convergence of the side walls has the further advantage that the upper and lower walls become isosceles trapezoids instead of oblongs. Hence in so far as they may be capable of sympathetic vibration, they tend to respond to a wide range of frequencies.

In Fig. 1 the dotted lines and arrows indicate in a suggestive though more or less inadequate manner the path of the main beam through the reflecting projector and also with less degree of completeness some of the forward diffusion from the front face $l-m$ of the main beam and also the face $n-o$. The curved lines $m-r$ and $o-r$ represent the wave fronts of these diffusions. These various sets of lines indicate that the main beam and all of the stronger portions of the forward diffusion, cross the plane of the mouth of the projector at comparatively high angles and at different angles and at different times. Thus the curvature of the wave front and its non-simultaneous passage of points where backward reflection might occur exists not only with reference to the dimensions illustrated in Fig. 2, but also with reference to the other dimension illustrated in Fig. 1.

As I have indicated herein and also in my patent above referred to, spring metal walls for any part of the widening conduit or projector are desirable, or even tolerable, only as a means for restoring to some kinds of music, some of the brilliant qualities

which have been lost in the recording and reproducing operations. Nevertheless, for speech and certain other records and for more perfect records which will doubtless become available in the future, and for telephone and radio reproducers, perfectly faithful undistorted amplifications may be found highly desirable. For such undistorted amplification I find that the walls of the widening conduit as well as of the projector should be very stiff and at the same time very light, so that tendency to sympathetic vibration will be avoided and such as may occur will be of the higher frequencies. To this end the quality of the material used should be very stiff and light as to quality, while the construction should be as solid as possible. For this purpose the best material which I have been able to find up to the present time, is boards or timbers of well seasoned spruce. Probably the thicker the timber is the better it would be, but experience shows that the above named thickness of an inch or two is practically sufficient for the walls of the widening conduit and the projector. In this connection it will be noted that throughout the widening conduit the exterior walls are almost as thick as the sound beam which is confined between them.

While I prefer the right angle reflectors 24, 25 turning the waves emerging from the slot outlet of widening conduit 10, through angles totaling 180 degrees, it will be found that curved or partly curved and partly plane deflectors can be used, as for instance, semi-cylindrical surfaces having an axis parallel with the slot outlet, centering at or near the point f , as indicated in dotted lines on Fig. 1. Curved surfaces of less angular arc or less radius or struck from a more remote center, are usable but less desirable. Where the conduit 10 is vertical, instead of inclined at a 45 degree angle, a single reflector may be used to turn the waves through the 90 degree angle, instead of two reflectors for the 180 degree angle, and such single reflector may be either plane or curved, or partly plane and partly curved. These and other similar modifications are based on my above explained principle that where the widening conduit is kept thin as compared with the phase lengths of the waves of the higher frequencies necessary to good reproduction, the conduit may be curved in the direction of its thinness, without great losses and without danger of serious phase displacement for the short lengths (high frequency) waves.

My invention does not depend upon the correctness of my theories with reference to it and in so far as I have stated theories, it has been for the purpose of indicating or accounting for novel results. Whether correct or not, they will be found useful as hypotheses to assist those skilled in the art when

seeking to apply one or more of my novel principles to new conditions or purposes.

In my prior application above referred to, I have described heavy stiff walls for the 5 widening conduit. While certain claims of said prior application are broad enough to cover this feature, the specific claims of said prior application are limited to the form in which the widening conduit has spring 10 walls adapted to add a brilliant quality to the reproduced sounds, but the specific claims for the widening conduit with the thick stiff walls are necessarily reserved for this separate application.

15 I claim:

1. A sound amplifying conduit for expanding the wave fronts of complex sound waves, said conduit being solidly constructed of thick, stiff, light material, and comprising a portion having walls arranged to 20 permit guided and limited but rapid expansion of the wave front in one dimension along widely diverging lines and other walls nearly parallel with each other, arranged to 25 guide said waves in the other dimension, thereby forming a thin sound beam with widely divergent flanks and a deeply curved wave front; and, as a continuation thereof, 30 a projector portion having walls diverging at an angle permitting guided but rapid expansion of said beam in said second dimension, one of said latter walls being integral with one of said nearly parallel walls and, 35 in combination therewith one or more piers rigidly secured near the outlet of said nearly parallel walls.

2. A sound amplifying conduit for expanding the wave fronts of complex sound waves, said conduit being solidly constructed of thick, stiff, light material, and comprising a portion having walls arranged to 40 permit guided and limited but rapid expansion of the wave front in one dimension along widely diverging lines and other walls nearly parallel with each other, arranged to 45 guide said waves in the other dimension, thereby forming a thin sound beam with widely divergent flanks and a deeply curved wave front; and, as a continuation thereof, 50 a projector portion having walls diverging at an angle permitting guided but rapid expansion of said beam in said second dimension, one of said latter walls being integral with one of said nearly parallel walls and, 55 in combination therewith one or more piers rigidly secured near the outlet of said nearly parallel walls, said piers being elongated in a direction parallel with the direction of the sound waves impinging thereon.

60 3. A sound amplifying conduit for expanding the wave fronts of complex sound waves, said conduit being solidly constructed of thick, stiff, light material, and comprising a portion having walls arranged to 65 permit guided and limited but rapid expansion

of the wave front in one dimension along widely diverging lines and other walls nearly parallel with each other, arranged to 70 guide said waves in the other dimension, thereby forming a thin sound beam with widely divergent flanks and a deeply curved wave front and, in combination therewith one or more piers rigidly secured near the outlet of said nearly parallel walls.

4. A sound amplifying conduit for expanding the wave fronts of complex sound waves, said conduit being solidly constructed of thick, stiff, light material, and comprising a portion having walls arranged to 75 permit guided and limited but rapid expansion of the wave front in one dimension along widely diverging lines and other walls nearly parallel with each other, arranged to 80 guide said waves in the other dimension, thereby forming a thin sound beam with widely divergent flanks and a deeply curved wave front and, in combination therewith one or more piers rigidly secured near the outlet of said nearly parallel walls, said piers being elongated in a direction parallel 85 with the direction of the sound waves impinging thereon.

5. A sound amplifying conduit for expanding the wave fronts of complex sound waves, said conduit being solidly constructed of thick, stiff, light material, comprising a portion having walls arranged to 90 permit guided and limited but rapid expansion of the wave front in one dimension along widely diverging lines and other walls nearly parallel with each other, arranged to 95 guide said waves in the other dimension, thereby forming a thin sound beam with widely divergent flanks and a deeply curved wave front and, as a continuation thereof, 100 a projector portion having walls diverging at an angle permitting guided but rapid expansion of said beam in said second dimension, one of said latter walls being integral with one of said nearly parallel walls and, 105 in combination therewith one or more piers rigidly secured near the outlet of said nearly parallel walls.

6. A sound amplifying conduit for expanding the wave fronts of complex sound waves, said conduit being solidly constructed of thick, stiff, light material, and comprising a portion having walls arranged to 110 permit guided and limited but rapid expansion of the wave front in one dimension along 115 widely diverging lines and other walls nearly parallel with each other, arranged to guide said waves in the other dimension, thereby forming a thin sound beam with widely divergent flanks and a deeply curved 120 wave front; and, as a continuation thereof, a projector portion having opposite walls diverging at an angle permitting guided but 125 rapid expansion of said beam in said second dimension, and other opposite walls are 130

ranged to confine and deflect inward the divergent flanks of said beam.

7. A sound amplifying conduit for expanding the wave fronts of complex sound waves, said conduit being solidly constructed of thick, stiff, light material, and comprising a portion having walls arranged to permit guided and limited but rapid expansion of the wave front in one dimension along widely diverging lines and other walls nearly parallel with each other, arranged to guide said waves in the other dimension, thereby forming a thin sound beam with widely divergent flanks and a deeply curved wave front; and, as a continuation thereof, a projector portion having opposite walls diverging at an angle permitting guided but rapid expansion of said beam in said second dimension, and other opposite walls arranged to confine and deflect inward the divergent flanks of said beam, said deflecting walls of the projector converging toward the mouth of the projector at substantial angles, whereby said diverging walls are of substantially decreasing width toward the mouth of the projector. 70

8. A sound amplifying conduit for expanding the wave fronts of complex sound waves, said conduit being solidly constructed of thick, stiff, light material, and comprising a portion having walls arranged to permit guided and limited but rapid expansion of the wave front in one dimension along widely diverging lines and other walls nearly parallel with each other, arranged to guide said waves in the other dimension, thereby forming a thin sound beam with widely divergent flanks and a deeply curved wave front; and, as a continuation thereof, a projector portion having opposite walls diverging at an angle permitting guided but rapid expansion of said beam in said second dimension, one of said latter walls being integral with one of said nearly parallel opposite walls, and other walls arranged to confine and deflect inward the divergent flanks of said beam. 85

9. A sound amplifying conduit for expanding the wave fronts of complex sound waves, said conduit being solidly constructed of thick, stiff, light material, and comprising a portion having walls arranged to permit guided and limited but rapid expansion of the wave front in one dimension along widely diverging lines and other walls nearly parallel with each other, arranged to guide said waves in the other dimension, thereby forming a thin sound beam with widely divergent flanks and a deeply curved wave front; and, as a continuation thereof, a projector portion having opposite walls diverging at an angle permitting guided but rapid expansion of said beam in said second dimension, one of said latter opposite walls being integral with one of said nearly 90

parallel walls, and other walls arranged to confine and deflect inward the divergent flanks of said beam and, in combination therewith one or more piers rigidly secured near the outlet of said nearly parallel walls. 70

10. A sound amplifying conduit for expanding the wave fronts of complex sound waves, said conduit being solidly constructed of thick, stiff, light material, and comprising a portion having walls arranged to permit guided and limited but rapid expansion of the wave front in one dimension along widely diverging lines and other walls nearly parallel with each other, arranged to guide said waves in the other dimension, thereby forming a thin sound beam with widely divergent flanks and a deeply curved wave front; and, as a continuation thereof, a projector portion having opposite walls diverging at an angle permitting guided but rapid expansion of said beam in said second dimension, one of said latter opposite walls being integral with one of said nearly parallel walls, and other walls arranged to confine and deflect inward the divergent flanks of said beam and, in combination therewith one or more piers rigidly secured near the outlet of said nearly parallel walls, said piers being elongated in a direction parallel with the direction of the sound waves impinging thereon. 80

11. A sound amplifying conduit for expanding the wave fronts of complex sound waves to a desired outlet area, said conduit comprising a primary expansion portion having walls arranged to permit guided and limited but rapid expansion of the wave front in one dimension along widely diverging lines to a width greater than that of the outlet, and other walls arranged to guide the waves in the other dimension, to form a thin sound beam with widely divergent flanks and a deeply curved wave front; and a secondary expansion portion or projector having opposite walls diverging at an angle permitting guided and limited but rapid expansion of said beam to the desired area in said second dimension, and other opposite walls arranged to confine the divergent flanks of said beam in said first dimension and to deflect them toward each other. 100

12. A sound amplifying conduit for expanding the wave fronts of complex sound waves to a desired outlet area, said conduit comprising a primary expansion portion having walls arranged to permit guided and limited but rapid expansion of the wave front in one dimension along widely diverging lines to a width greater than that of the outlet, and other walls arranged to guide the waves in the other dimension, to form a thin sound beam with widely divergent flanks and a deeply curved wave 110

115

120

125

130

- front; and a secondary expansion portion or projector having opposite walls diverging at an angle permitting guided and limited but rapid expansion of said beams to the desired area in said second dimension, and other opposite walls arranged to confine the divergent flanks of said beam in said first dimension and to deflect them toward each other at angles predetermined with respect to the width and depth of the projector portion to cause the lines of reflection of said flanks to cross each other and diverge at high angles, within the mouth of the projector.
18. A sound amplifying conduit for expanding the wave fronts of complex sound waves to a desired outlet area, said conduit comprising a primary expansion portion having walls arranged to permit guided and limited but rapid expansion of the wave front in one dimension along widely diverging lines to a width greater than that of the outlet, and other walls arranged to guide the waves in the other dimension, to form a thin sound beam with widely divergent flanks and a deeply curved wave front; and a secondary expansion portion or projector having opposite walls diverging at an angle permitting guided and limited but rapid expansion of said beams to the desired area in said second dimension, and other opposite walls arranged to confine the divergent flanks of said beam in said first dimension and to deflect them toward each other at angles predetermined with respect to the width and depth of the projector portion to cause the lines of reflection of said flanks to cross each other and diverge at high angles, within the mouth of the projector, yet clearing the edges of the convergent walls at the mouth of the projector.
14. A sound amplifying conduit for expanding the wave fronts of complex sound waves to a desired outlet area, said conduit being solidly constructed of thick, stiff material and comprising a primary expansion portion having walls arranged to permit guided and limited but rapid expansion of the wave front in one dimension along widely diverging lines to a desired width, and other walls arranged relatively parallel to guide the waves in the other dimension, thereby forming a thin sound beam with widely divergent flanks and a deeply curved wave front; means for deflecting said beam through a wide angle in the direction of its thinness; and a secondary expansion portion or projector having walls diverging at an angle permitting guided and limited but rapid expansion of said beams to the desired area in said second dimension.
15. A sound amplifying conduit for expanding the wave fronts of complex sound waves to a desired outlet area, said conduit being solidly constructed of thick, stiff ma-
- terial and comprising a primary expansion portion having walls arranged to permit guided and limited but rapid expansion of the wave front in one dimension along widely diverging lines to a desired width, and other walls arranged relatively parallel to guide the waves in the other dimension, thereby forming a thin sound beam with widely divergent flanks and a deeply curved wave front; and a secondary expansion portion or projector having walls diverging at an angle permitting guided and limited but rapid expansion of said beams to the desired area in said second dimension, one of said latter walls extending reversely at a very acute angle to said relatively parallel walls and having a substantial portion of its length integral with one of them.
16. A sound amplifying conduit for expanding the wave fronts of complex sound waves to a desired outlet area, said conduit being solidly constructed of thick, stiff material and comprising a primary expansion portion having walls arranged to permit guided and limited but rapid expansion of the wave front in one dimension along widely diverging lines to a desired width, and other walls arranged relatively parallel to guide the waves in the other dimension, thereby forming a thin sound beam with widely divergent flanks and a deeply curved wave front; and a secondary expansion portion or projector having walls diverging at an angle permitting guided and limited but rapid expansion of said beams to the desired area in said second dimension, one of said latter walls extending reversely at a very acute angle to said relatively parallel walls and having a substantial portion of its length integral with one of them, in combination with rigid piers secured between said nearly parallel walls, to stay the free edge of said integral wall against sympathetic vibration.
17. In the combination specified by claim 14, the further feature of a plane reflector in the projector for directing the laterally expanded sound beam to said diverging walls for expansion in the other dimension.
18. In the combination specified by claim 14 the further feature of arranging the parts so that the sound beam is projected along one of the diverging walls of the mouth of the projector.
19. In the combination specified by claim 14 the further feature of having the projector directed upward so that the emerging sound waves are projected upward and at considerable angles to the plane of the mouth of the projector for the purpose described.
20. A projector solidly constructed of thick, stiff material and comprising two high angle reflecting surfaces on the same side of the projector, the second reflector

being in receiving relation for reflection from the first reflector, and a widening conduit for impinging a thin, wide sound beam, less than 2 inches thick and very wide as compared with its thickness, at a high angle upon the first of said reflectors.

21. In a sound amplifier, a sound reflecting surface, and a flat walled expansion conduit leading thereto, solidly constructed of thick, stiff material and having two opposite approximately parallel walls for a considerable distance backward from the reflector, said sound reflecting surface being rigidly secured in fixed angular relation with the outlet of said expansion conduit.

22. A sound amplifier comprising a primary expansion conduit leading downward from the tone arm solidly constructed of thick, stiff material and adapted to expand the sound waves rapidly in one dimension without substantial expansion in the other dimension to project a relatively wide thin sound beam, in combination with a plane reflector arranged to deflect said sound beam in the direction of its thinness and a second plane reflector in receiving relation to the first reflector and arranged to reflect said sound beam through a further angle in the same direction.

23. A primary expansion conduit solidly constructed of thick, stiff material, having opposite walls diverging in one dimension much more than in the other dimension to project a relatively thin sound beam, in combination with a projector having two adjacent reflectors at a high angle to one another on the same side of the projector.

24. A sound projector solidly constructed of thick, stiff, light material and comprising a thin flat expansion conduit, rapidly diverging to great width as compared with its thickness, its thickness being less than 2 inches, the conduit being curved in the direction of its thinner dimension and discharging into a shorter conduit having a wide expansion angle in the direction of said thinner dimension.

25. A sound amplifying conduit for expanding the wave fronts of complex sound waves to a desired area, said conduit comprising a primary expansion portion having walls arranged to permit guided and limited but rapid expansion of the wave front in one dimension along widely diverging lines; and a secondary expansion portion wherein said walls converge in the latter dimension to confine and deflect inward the divergent flanks of said beam, the length and angle of the convergence of said converging portions being predetermined with reference to the

width and angle of the divergence of said diverging portions so that said converging portions intercept and deflect toward each other approximately one-half the wave front projected from said primary expansion portion, while the total cross-sectional area continues increasing throughout.

26. In a method of sound wave amplification the step of expanding sound waves between substantially non-vibratory walls, causing their expansion in substantially one dimension only, then expanding them again in substantially another dimension only.

27. A method of sound wave amplification within confining channels whose walls are designed and constructed to reduce the effect of vibration, comprising the steps of first expanding the waves in one dimension in one stage, and then in a succeeding stage expanding them in another dimension only.

28. In a method of sound wave amplification the step of expanding the sound waves between sensibly non-vibratory walls, causing their expansion in substantially one dimension only, deflecting them in the direction of their thinness and then expanding them again in substantially another dimension only between sensibly non-vibratory walls.

29. A method of sound wave amplification in confining channels whose walls are sufficiently rigid to be substantially non-resilient to audible vibrations, comprising the steps of causing at least two distinct and successive stages of expansion, one stage in which the waves are expanded in one dimension, deflected in the direction of their thinness, and then after such deflection a succeeding stage in which the waves are expanded in another dimension only.

30. A method of amplifying sound waves causing substantially uni-dimensional expansion only of the waves in successively different dimensions through conduits sensibly non-vibratory.

31. A method of sound wave amplification comprising expanding the waves in a channel whose walls are sufficiently rigid to be substantially non-resilient to audible vibrations, causing at least two distinct and successive stages of expansion, first expanding the waves substantially in one dimension only, then deflecting them in the direction of their thinness, and then expanding the waves substantially in another dimension only in a succeeding stage.

Signed at Buffalo in the county of Erie and State of New York this 8th day of December, A. D. 1923.

ELWOOD GRISSINGER.
